UNITED STATES PATENT OFFICE.

CHARLES I. E. MASTIN, OF MIDLAND PARK, NEW JERSEY.

SIGN PLATE AND METHOD OF MAKING THE SAME.

Application filed July 5, 1923. Serial No. 649,436.

To all whom it may concern:

Be it known that I, CHARLES I. E. MASTIN, a citizen of the United States, residing at Midland Park, in the county of Bergen and State of New Jersey, have invented certain new and useful Improvements in Sign Plates and Methods of Making the Same, of which the following is a specification.

This invention relates to sign-plates, and 10 it has reference in particular to sign-plates which require to be handled considerably in use and are thus likely to be damaged, as for instance the sign or signal device used by railroad-crossing guards, which at present are plain disks or sheets having the sign characters printed or painted thereon. The 15 object of the invention is to provide a sign-plate which shall be practically imperishable and especially not likely to be damaged 20 due to rough handling in use. The invention is shown applied to a sign-plate used by a railroad-crossing guard, but it may be applied, of course, to other signs.

In the drawing,

25 Fig. 1 is a front elevation, partly broken away, of the improved sign-plate;

Fig. 2 is a substantially central horizontal section;

30 Fig. 3 is a fragmentary enlargement of Fig. 2;

Fig. 4 is a longitudinal section of the handle; and

Fig. 5 is a section on line 5—5, Fig. 1.

To form a sign-plate which is light and 35 yet as strong and durable as possible it is the present practice to use a plate of metal, as sheet-metal, and coat it with a protecting covering of paint. If it is sufficiently light such a plate may be easily bent and becomes 40 damaged in that way; also the paint sooner or later wears off or chips away, leaving the plate exposed and subject to corrosion and the letters or other sign-characters in part or wholly obliterated. To produce a sign-plate lacking these defects I proceed as follows:

A reticulated planiform core is provided 45 by punching a stiff metal plate *a* with numerous holes *b*. Also there are provided two thin sheets *c* of rubber of approximately the same area and size as the plate *a*. Raw rubber is preferred because then the surfaces of the two sheets which adjoin each other 55 will be adhesive and the sheets will be in practically a state of cohesion when the sheets are pressed together, as in the process

of vulcanizing, and because of its great toughness when vulcanized, especially when the vulcanizing treatment leaves it pliable so that it lacks brittleness and so would not fracture in flexing it.

These three, the plate and the sheets, are then assembled so that the plate lies between the sheets and the edges of all three are in approximate registry with each other, and in a suitable vulcanizing press they are then subjected to pressure such that the portions of the sheets opposite the holes in the plate are by the pressure welded together, as at *c'*, so that the two sheets become practically integral at each hole. An adhesive *d* may be employed to insure union where each sheet is opposed by the material of the plate between its holes.

This obviously produces a very strong but light sign-plate, upon which the sign characters may be placed in any way (the preferred way being hereinafter explained). The tough plastic coating of vulcanized rubber is not adapted under ordinary rough handling to break or chip away, nor is the sign-plate easily bent because of the resistance offered by the coating, and if it should be bent the coating will not crack or craze. Because the two plastic sheets are united at many places (as *c'*) throughout the area of the sign-plate they cannot warp away from plate *a*.

It is very desirable to provide a sign-plate 50 of this character with an edge-fillet or bead which shall stand from at least on face thereof to additionally reinforce it marginally and also so as to protect the sign-characters placed on the sign-plate against the effects of rubbing the latter over any surface and in which the edge of plate *a* will be embedded. I therefore provide such a fillet *e* as an integral part of the rubber coating. This is molded on the sign-plate when the plate *a* and two plastic sheets are subjected 55 to the uniting pressure in the vulcanizing, as described, as by forming mating grooves in the pressure members of the press with which the approximately registering margins of the plate and sheets are made to coincide or register and by application of the pressure squeezing the material of the sheets to such an extent that outward of the margin of the plate the sheets are united by pressure and said material flows outwardly, radially 60 in all directions, into the opposed grooves and ultimately filling them.

A handle may be provided in any way. In the preferred form this is composed of a metal tube *f* which has a longitudinal slot *g* in one end, enlarged at *g'* to accommodate the fillet *e* and a coating of vulcanized rubber *h* formed on the tube as a core; the coated tube is slipped over the edge of the sign-plate, as shown in Fig. 1, and then a bolt or other securing device *i* is passed 10 through the parts to clamp them together.

The sign-characters may be painted or otherwise placed on the sign-plate, but I prefer to form them from raw rubber, as by providing suitable pieces of this material 15 and placing them in the vulcanizing press with the parts *c a c* so that when the vulcanizing is done, under pressure, they will adhere to and become substantially integral with one or both of the sheets *c*, according as 20 one or two sets of the pieces are used for one or both faces of the finished product. Sign-characters so formed cannot be obliterated or mutilated in ordinary use. It will be understood that the surface of each sign-character is depressed below the fillet-plane, so 25 that they cannot touch a plane surface on which the sign-plate may be placed.

Having thus fully described my invention, what I claim as new and desire to secure by 30 Letters Patent is:—

1. A sign-plate consisting of a stiff reticulated plate forming a core and coating bodies of tough plastic material preformed as sheets covering the two faces of the plate and having 35 their adjoining surface portions adhesive and adhering to each other through the holes of the plate.

2. A sign-plate consisting of a stiff reticulated plate forming a core and coating bodies 40 of tough pliable plastic material preformed as sheets covering the two faces of the plate and having their adjoining surface portions adhesive and adhering to each other through the holes of the plate.

45 3. A sign-plate consisting of a stiff reticulated plate forming a core and coating bod-

ies of tough pliable vulcanized rubber preformed as sheets covering the two faces of the plate and having their adjoining surface portion adhesive and adhering to each other 50 through the holes of the plate.

4. A sign-plate consisting of a stiff reticulated plate forming a core and coating sheets of tough plastic material covering the two faces of the plate and adhered to 55 each other through the holes of the plate, said sheets having their margins pressed into substantially integral union with each other.

5. A sign-plate consisting of a stiff reticulated plate forming a core and coating 60 sheets of tough plastic material covering the two faces of the plate and integrally united with each other through the holes of the plate, said sheets having their margins pressed into substantially integral union 65 with each other and forming a fillet portion in which the edge of said plate is embedded.

6. A reinforced planiform body including a stiff plate and coating sheets of tough plastic material covering the two faces of 70 the plate, said sheets having their margins pressed into substantially integral union with each other and forming a fillet portion in which the edge of said plate is embedded.

7. A reinforced planiform body including a stiff plate and coating sheets of tough pliable plastic material covering the two faces of the plate, said sheets having their margins pressed into substantially integral union with each other and forming a fillet 80 portion in which the edge of said plate is embedded.

8. In combination, with a sign-plate comprising a stiff plate forming a core and a coating of tough plastic material covering 85 its two faces, a handle secured to the sign-plate and consisting of a tubular core having a slot in one end receiving the sign-plate and a coating of tough plastic material covering the core. 90

In testimony whereof I affix my signature.

CHARLES I. E. MASTIN.
